ELECTRIC SWITCH

Filed April 18, 1923

UNITED STATES PATENT OFFICE.

ELLSWORTH FROST MINER, OF LITCHFIELD, CONNECTICUT.

ELECTRIC SWITCH.

Application filed April 18, 1923. Serial No. 632,932.

This invention relates to electrical circuit makers and breakers and, more particularly, to electrical switches.

One of the objects of the invention is to provide an improved construction and arrangement of parts for an electric switch.

Another object of the invention is to provide an improved form of switch which may be locked in one of its operative positions.

Another object of the invention is to provide a convenient form of electric switch adapted to be used in connection with testing apparatus.

Still another object of the invention is to provide an improved form of electric switch having normal and alternate positions and arranged and constructed so that in order to throw the switch from normal to alternate position a specified form of key device must be used, and this key device cannot be removed from the switch until the latter has been thrown into normal position and locked, this key device being of such construction that it will also prevent closing and sealing of the switch until the key device has been removed therefrom; all of which means that the switch cannot through negligence or deliberate intent, be closed and sealed except when the switch is in normal position.

A more specific object of the invention is, to provide an improved form of electric switch for use in connection with electric service meters, and which is reasonably proof against current theft.

Other objects will be in part obvious, and in part pointed out hereinafter.

The invention, accordingly, consists in the features of construction, combination of elements and arrangement of parts which will be exemplified in the construction herein-after set forth, and the scope of the application of which will be indicated in the appended claims.

In the drawing forming a part of the specification, and in which similar reference characters refer to similar parts.

Fig. 1 is a plan view of a switch embodying the features of the invention and adapted to be used in connection with an electric service meter, the switch being in its normal position;

Fig. 2 is a plan view of the switch shown in its alternate or meter testing position;

Fig. 3 is a cross section of the switch along the line 3—3 of Fig. 1 and shows the manner

in which the switch blade and the contacts co-operate.

Fig. 4 is a sectional view along the line 4—4 of the locking device Fig. 1, by means of which the switch is held in its normal position, and a key plug for operating the locking device and for completing the testing circuit of the service meter; and

Fig. 5 is a diagrammatic showing of the manner in which the switch is associated with the current leads, service meter and the customer's circuit.

Referring to the drawing, and more particularly to Figs. 1, 2, 3 and 4, there is illustrated a form of switch particularly adapted for use in connection with an electric service meter of the type commonly used for measuring the amount of current consumed by the customer for electric light or similar purposes. My improved switch is susceptible of general use, but for the purpose of disclosing one of its many applications, it is here illustrated as associated with a service meter, but it is to be understood that its use is not limited thereto. The switch is housed within a suitable casing 10 and is provided with suitable binding posts 11, 12 and 13 which are adapted to be connected with respect to each other in a normal and alternate manner by means of a switch blade 14.

The circuit changes effected by means of this switch make it possible to temporarily disconnect the meter from the house circuit for testing purposes, without interrupting the supply of current to the customer. By referring to Fig. 5, the meter, indicated at 15, may be disconnected by throwing the switch blade 14 to its alternate position, thus completing a circuit directly through terminals 11 and 13, leaving the terminal 12 disconnected from the house circuit. While the circuit of the customer is still supplied with current the meter 15 may be tested by connecting a suitable lead from the testing instrument to the terminal 12.

The switch member 14 is shaped somewhat in the form of an anchor, being pivoted at the stem end on the terminal 13, these parts corresponding to the flukes extending generally circularly about the terminal 13 as a center. The member 14 is constructed of conductive material, and is faced on its under side for approximately half the length of its free end with insulating material 16 so that when thrown to its alternate position at the left

the switch member is prevented from contacting with the terminal blade 17 upon which the terminal 12 is mounted. When in this latter position the contact face 18 on the end 5 of the switch member is adapted to engage the terminal 11 to complete a circuit from the terminal 11 to the terminal 13 through the switch member 14. The terminal plate 17 is provided with an upwardly projecting contact face 19 which is adapted to complete the circuit from the terminal 12 through the body 10 of the switch 14 to the terminal 13 when the switch is in its normal position. The switch member 14 is also provided with a shield or strip of insulating material 21 which protects the terminal 11 from being tampered with when the switch is in its normal position. When the switch is thrown in its alternate position access to the terminal 11 is permitted 15 through an aperture 22 in the strip 21 which registers with the terminal 11.

In order to prevent the switch from being operated by unauthorized persons, there is provided a locking means to hold the switch 25 in its normal position. This means comprises a latch 23 pivotally mounted on the terminal plate 17 by means of a screw 24, and which is adapted to rotate into and out of engaging 30 relation with a stud 26 integrally formed on the lower face of the switch member 14. This latch 23 is adapted to be rotated by means of a plug 27 of suitable insulating material which may be inserted through a circular aperture 28 in the switch member 14 when 35 the latter is in its normal position. When so inserted, a pin 29 projecting from the lower face of the plug 27 is adapted to engage with a corresponding hole in the latch 23. Rotation of the plug 27 will, therefore, turn the 40 latch 23 so that it no longer engages the stud 26, and the switch may then be operated. The plug 27 is also provided with a lateral 45 projection 31 which prevents the removal of the plug from the aperture 28 when it has disengaged the latch 23. In order that the switch blade 14 may be thrown while the plug 27 is inserted therein, there is provided in the switch blade a slot 32 which is a continuation of the aperture 28, but of slightly narrower 50 width. Grooves 33 are provided in the plug 27 so that when the plug is turned to unlock the latch 23 these grooves engage the sides of the slot 32 and permit throwing of the switch 55 14. In this position, the plug 27 can neither be turned nor removed, being held fast by the edges of the slot 32 engaging in the grooves of the plug. The stud screw 34 serves 60 as a guide for the switch member 14, and also to secure this member in position, there being provided a slot 36 with which this screw is adapted to co-operate. When the switch member 14 is in its normal position the plug 27 is also prevented from being removed 65 without operating the latch 23 by means of the lateral projection 31 on its lower edge.

This projection is so positioned that when the latch 23 is in engagement with the stud 26 it registers with the slot 32, thus permitting the plug to be readily removable. At any other position removal of the plug is 70 positively prevented, since the projection 31 engages with the lower face of the switch member 14.

The plug 27 also provides a means for connecting a test instrument with the terminal 12 for the purpose of testing the meter 15, and to this end there is provided a contact member within the plug which is adapted to engage the head of the screw 24, and which is provided with a suitably insulated cord 39 80 extending through the plug 27 for attachment to such testing instrument.

The operation of the switch is as follows: Assuming the switch to be in its normal operating position as shown in Fig. 1, the plug 27 is inserted into the aperture 28 until the pin 29 engages with the latch 23. The plug is then turned to disengage the latch, and the switch blade 14 is pushed to the left permitting the edges of the slot 32 to engage the 90 plug at the grooves 33. The switch blade 14 is rotated to position shown in Fig. 2 whereat the terminal 11 is directly associated with the terminal 13 through the medium of the switch blade 14. This leaves the terminal 12 disconnected from the other terminals and the meter no longer records the current used in the consumer's circuit. The meter 15 is now in condition to be tested by means of a suitable testing instrument connected therewith through the conductor 39. With the switch in this position, the plug 27 cannot be removed or rotated except on the return of the switch blade 14 to its normal position because of the engagement of the edges of the 95 slot 32 in the grooves 33. Upon returning the switch to its normal position the plug 27 may then be turned to engage the latch 23 with the stud 26, locking the switch against further movement, and permitting the removal of the 100 plug therefrom.

The plug 27 is preferably long so as to project sufficiently to prevent closing of the cover 41. This prevents the test man from leaving the test plug inserted in the switch, 115 since with the plug there within, the cover of the box cannot be closed and sealed. It will thus be seen that before the test man can close and seal the casing 10, it is absolutely necessary for him to throw the switch 120 into normal position, and then remove the test plug, insuring that by no possibility, either through negligence, forgetfulness or wantonness, can the switch box be sealed with the meter disconnected; thus the consumer cannot obtain current without charge, and the supplying company is protected 125 against loss.

It is also highly improbable that the usual customer would be well enough acquainted 130

with the details of the locking mechanism to unlock the switch so that it could be thrown into its alternate position disconnecting the meter. For this reason the switch is practically proof against current theft and operation by unauthorized persons.

Thus by the above construction are accomplished among others the objects hereinbefore referred to.

10 As many changes could be made in the above construction and many apparently widely different embodiments of this invention could be made without departing from the scope thereof, it is intended that all matter contained in the above description or shown in the accompanying drawing shall be interpreted as illustrative, and not in a limiting sense.

It is also understood that the language 20 used in the following claims is intended to cover all of the generic and specific features of the invention herein described and all statements of the scope of the invention which, as a matter of language, might be 25 said to fall therebetween.

I claim as my invention:

1. In combination, an electrical switch having normal and alternate circuit making positions, a locking device operable when said switch is in normal position, a key member for operating said locking device and insertable in said switch when in said normal position, and a casing for said switch including a cover, said key member being arranged to prevent closing of said cover when inserted in said switch.

2. In combination, an electrical switch having normal and alternate circuit making positions, a locking device for said switch, a key member for operating said locking device, and removable from said switch only when in said normal position, and a casing for said switch including a cover, said key member being arranged to prevent closing of said cover when inserted in said switch.

3. In combination, an electrical switch having normal and alternate circuit making positions, a locking device for said switch, a key member for operating said locking device and insertable in said switch only when in said normal position and removable therefrom only when said switch is in normal position and said locking device is in locking position, and a casing for said switch including a cover, said key member being arranged to prevent closing of said cover when inserted in said switch.

4. In combination, an electrical switch having normal and alternate circuit making positions, a locking device for said switch, a key member for operating said locking device, insertable and removable from said switch only when in said normal position, and a casing for said switch including a cover, said key member being arranged to

prevent closing of said cover when inserted in said switch.

5. In a device of the character described, a switch member having normal and alternate circuit making positions, and provided with a slot therewithin, a locking device for said switch member, a key member insertable in said slot to release said locking device, and provided with slots adapted to receive the sides of said slot when said switch member is in its alternate position.

6. In a device of the character described, a switch member pivotally mounted to move between normal and alternate circuit making positions, and provided with a slot in its movable end, a latch to hold said switch member in its normal position, a key member insertable in said slot and adapted upon rotation to release said latch, said key member being provided with grooves to receive the edges of said slot when said switch member is moved from its normal position whereby said key member is held against removal except when said switch member is in its normal position.

7. In a device of the character described, a switch member pivotally mounted to move between normal and alternate circuit making positions, and provided with a slot in its movable end, a latch to hold said switch member in its normal position, a key member insertable in said slot and adapted upon rotation to release said latch, said key member being provided with grooves adapted to receive the side edges of said slot when said switch member is moved from its normal position, whereby said key member is held against removal except when said switch member is in its normal position, and means associated with said key member and co-operative with said switch member to prevent the removal of said key member from said switch member when said latch is released.

8. In a device of the character described, a switch member having normal and alternate circuit making positions, a normal contact and an alternate contact therefor, and a shield carried by said switch member to cover said alternate contact when said switch member is in its normal position.

9. In a device of the character described, a switch member having normal and alternate circuit making positions, a normal contact and an alternate contact therefor, said switch member comprising portions adapted to contact with said normal and alternate contacts, an insulating portion to prevent contact with said normal contact when said switch member is in its alternate position, and a shield to protect said alternate contact when said switch member is in its normal position.

10. In a device of the character described, a switch member having normal and alternate circuit making positions and provided

- with a slot therein, normal and alternate contacts for said switch member, a locking device to hold said switch member in its normal position, and a circuit making plug key member insertable in said slot to engage one of said contacts, and adapted to release said locking device, and means to hold said plug against removal from said contact when said switch member is out of its normal position.
- 10 11. In a device of the character described, a switch member having normal and alternate circuit making positions and provided with a slot therein, normal and alternate contacts for said switch member, a locking device to hold said switch member in its normal position, and a circuit making plug key member insertable in said slot to contact with one of said contacts and adapted to disengage said locking device, said plug being provided with

grooves to be engaged by said switch member 20 when the latter is out of its normal position.

12. In a device of the character described, a switch member having normal and alternate circuit making positions and provided with a slot therein, normal and alternate contacts for said switch member, a locking device to hold said switch member in its normal position, and a circuit making plug key member insertable in said slot to contact with one of said contacts and adapted to disengage said locking device, said plug being provided with grooves to be engaged by said switch member 25 when the latter is out of its normal position, and a lateral projection on said plug to prevent removal thereof from said slot except 30 when said device is in its locking position and said switch is in its normal position.
